MOTOR COACH

Harry Zoltok, Winnipeg, Manitoba, Canada, assignor to Motor Coach Industries Limited, Winnipeg, Manitoba,
Canada

Filed June 19, 1967, Ser. No. 7,514

Term of patent 14 years

(Cl. D14—3)

The dominant features of the design reside in the portions shown by full lines.

I claim:

The ornamental design for a motor coach, as shown and described.
